8 Claims. (Cl. 208—321)

This invention relates to the separation of liquid mixtures with a selective solvent. More particularly, it relates to the separation of aromatic hydrocarbons from mixtures with other hydrocarbons by solvent extraction with furfural, distillation of the resulting extract-solvent mixture in the presence of the water vapor, and condensing and separating a portion of the furfural in the absence of a liquid water phase. In one embodiment of this invention, naphthalene and alkyl naphthalenes are separated from gas oils by selective solvent extraction with furfural, the dissolved aromatics are concentrated and separated by a highly selective azeotropic distillation in the presence of furfural employing added steam, and a portion of the furfural is separately condensed and separately withdrawn in the absence of a liquid water phase.

Gas oils from some aromatic crude sources and gas oils from thermal and catalytic cracking contain substantial quantities of useful aromatic hydrocarbons, for example, benzenoid, naphthalene, and naphthalenic hydrocarbons. This invention is particularly useful in the separation of naphthalene and naphthalene precursors, that is, naphthalenic hydrocarbons which may be converted to naphthalene, for example by hydrodealkylation. The desirable aromatics are diluted with nonaromatic hydrocarbons of the same boiling range making their separation by simple distillation impossible. It is an object of this invention to separate aromatic hydrocarbons in concentrated form from mixtures with nonaromatic hydrocarbons. Other objects will be apparent from the following description and claims.

Solvent extraction is a well known process for the separation of aromatic hydrocarbons from mixtures with nonaromatic hydrocarbons of similar boiling range. Furfural has been found to be an excellent selective solvent in the separation of hydrocarbons of relatively high boiling point, for example, hydrocarbons useful in the manufacture of lubricating oils and catalytic cracking feed stocks. Furfural extraction has also been found useful in the manufacture of kerosene and low boiling gas oil products where a raffinate of low aromatic content is produced. However such lower boiling hydrocarbons, for example, those boiling within the range of 400 to 600° F. are considerably more soluble in furfural than lubricating oils or cracking feed stocks. At temperatures above about 100° F. both aromatic and nonaromatic hydrocarbons boiling in the range of 400 to 600° F. are relatively soluble and the selectivity for aromatic hydrocarbons is relatively decreased. Although substantially complete separation of aromatics from raffinate streams may be readily effected, nonaromatics are dissolved in the extract to an extent that it is not possible to separate extract fractions containing aromatics in a concentration above about 80 percent at conditions readily obtained with ordinary cooling water. For the separation of aromatics in a concentration above 80 percent, high solvent selectivity is necessary which in turn requires temperatures far below usual ambient atmospheric temperatures, for example, about 30° F. At these low temperatures the solvency of the furfural is substantially reduced so that high solvent ratios, for example, about 250 percent or higher are required to obtain acceptable yields.

In accordance with this invention, a liquid hydrocarbon mixture containing aromatic and nonaromatic hydrocarbons is contacted with liquid furfural effecting formation of a raffinate mix comprising a major portion of the non-aromatic hydrocarbons and an extract mix comprising a furfural phase containing dissolved hydrocarbons containing 70 to 85 volume percent aromatic hydrocarbons and the remaining nonaromatic hydrocarbons. The extract mix contains within the range of about 60 to 85 volume percent of furfural. At least a part of said extract mix is distilled in a distillation zone in the presence of furfural and added water vapor (steam) effecting separation of an azeotropic mixture comprising water, a major portion of the nonaromatic hydrocarbons present in the extract mix and a portion of the furfural as distillate. Aromatic rich hydrocarbons and remaining furfural are separated as a bottoms fraction. Said bottoms are stripped separating a furfural stream in the absence of a liquid water phase and aromatic rich hydrocarbons.

20 In the extract mix azeotropic distillation step, water, preferably as steam, is added at a rate within the range of about 0.05 to 3.0 pounds per pound of extract mix. The water carries a portion of the hydrocarbon oil into the rectification section of the distillation tower and the furfural effects reduction of the relative volatility of the aromatic constituents of the distilland so that nonaromatic hydrocarbon constituents are concentrated in the distillate and aromatic hydrocarbon constituents are concentrated in the bottoms. The distillation is conducted to remove 30 within the range of about 3.0 to 30.0 volume percent of the furfural in the extract mix as distillate. The distillate, upon condensation, separates into three phases, an oil phase, a water phase and a furfural phase. The oil phase contains dissolved water and furfural in an amount of about 0.1 to 0.5 and 1.0 to 5.0 volume percent respectively. Similarly the water phase contains about 2.0 to 6.0 and 8.0 to 10.0 volume percent dissolved oil and furfural respectively and the furfural phase contains about 4.0 to 10.0 and 4.0 to 9.0 volume percent dissolved oil and water respectively. Solvent is readily recovered from the water phase by azeotropic distillation and from the oil phase by water washing.

The solvent phase is treated to remove water and oil since these constituents interfere with the effectiveness of the solvent. For example, water in the solvent reduces its solvent power and may separate in the extraction tower forming a third phase which interferes with the contact of the solvent and hydrocarbon phases. Oil dissolved in the solvent phase is even more troublesome since if not removed oil boiling near the boiling point of the solvent increases in concentration until an equilibrium is reached and the solvent becomes inefficient in extracting the aromatic components of the feed. This dissolved oil and water are concomitantly removed by distillation with added steam to separate oil, water and furfural azeotrope as distillate from furfural bottoms which are substantially free of dissolved oil and water.

In accordance with this invention, the extract mix azeotropic distillation step is effected with a minimum amount of steam and reboiler heat to effect separation of nonaromatic hydrocarbons overhead in an amount effective to increase the aromatic content of the hydrocarbon in the bottoms to the desired level but without distilling overhead more furfural than is necessary to form the azeotrope. In this manner, a relatively large portion of the furfural remains in the extract mix. The remaining extract mix is then distilled without adding steam to separate furfural from the aromatic concentrate. Since no steam is used in this final distillation, a sharp separation between furfural and oil is obtained and the furfural distillate contains less than 0.1 volume percent dissolved

water and less than 1.0 volume percent dissolved oil. By effecting the separation of furfural from the extract mix in two steps of azeotropic distillation followed by a "dry" distillation, substantial savings in utilities consumption and equipment cost are realized as compared with the separation of all of the furfural in the azeotropic distillation. The two step separation of furfural provides a furfural stream which is substantially dry and oil-free and a relatively small amount of furfural phase requiring treatment for separation of oil and water whereas if all of the furfural is distilled overhead in the extract mix azeotropic distillation column, all of the furfural from the extract mix is collected in contact with water and oil phases and must be distilled a second time. Additionally, a greater amount of water phase and oil phase are formed in this redistillation which must also be handled.

An advantage of the process of this invention is that aromatic concentrates containing more than 80 and preferably more than 90 percent aromatics may be separated from gas oil boiling range hydrocarbons with furfural employing temperatures about usual ambient atmospheric temperatures and moderate solvent rates.

Another advantage of the process of this invention is that a single solvent is employed as both a selective solvent in an extraction step and as a component of the azeotropic mixture in an azeotropic distillation step.

Another advantage is that a stream of furfural is separated out of contact with a liquid water phase thereby producing a furfural stream containing relatively little oil and water and reducing the oil and water content of this circulating solvent stream.

The accompanying drawing diagrammatically illustrates one form of the process of this invention. Although the drawing illustrates one arrangement of apparatus in which the process of this invention may be practiced, it is not intended to limit the invention to the particular materials or apparatus described.

A gas oil feed is passed through line 1 into extraction tower 11. In tower 11 the oil feed is contacted with liquid furfural in countercurrent flow. The furfural solvent may be "dry," that is, substantially free of dissolved water, or "wet," that is, containing some dissolved water, as is well known in the art of solvent extraction with furfural. Furfural introduced into tower 11 through line 2 at a rate of about 100 to 300 volume percent of the oil feed. In extraction tower 11 aromatic components of the oil feed are preferentially dissolved in the furfural and aromatic rich extract mix is withdrawn from the bottom of tower 11 through line 3. Raffinate oil denuded of aromatics is removed from the top of tower 11 through line 4 and discharged to raffinate recovery facilities for removal of the small amount of dissolved furfural by conventional means. A temperature gradient of up to about 50° F. and preferably within the range of about 10 to 30° F. is maintained in tower 11. A desired temperature gradient may be maintained by heating the furfural passed to the top of the tower in exchanger 5 and cooling the bottom of the tower with water in coil 6. Desirably the temperature of the tower bottom is maintained as low as possible with cooling water, for example, about 80 to 100° F. When ambient atmospheric temperatures and dew points are too high to obtain cooling water of desired temperature from a conventional cooling tower or spray pond, the cooling water may be chilled by vacuum flashing, for example, water may be cooled to 60° F. by discharge to a vacuum zone maintained at a pressure of 0.256 pounds per square inch absolute.

Extract mix is passed through line 3, preheater 16, and line 17 to extract-azeotrope tower 18. Tower 18 comprises a fractional distillation tower provided with a reboiler 20. Steam is introduced through line 21 to assist in distillation and provide the water required to satisfy the ternary azeotrope composition of hydrocarbon, furfural, and water. This azeotrope is removed as overhead vapor from tower 18 through line 22. The hydrocarbon-water-

furfural azeotrope comprises a part nonaromatic components and a part of the hydrocarbon extract and is distilled as overhead product leaving the remaining furfural and aromatic hydrocarbon components of the extract as bottoms product. The presence of furfural enhances the relative volatility of nonaromatic hydrocarbons as compared with the aromatic hydrocarbons so that the nonaromatic hydrocarbons appear in the azeotropic mixture taken overhead and the aromatics are concentrated in the bottoms. Aromatic concentrate and remaining furfural are removed from the bottom of tower 18 through line 19.

Azeotrope vapors from tower 18 are discharged through line 22, cooled in condenser 25, and the resulting condensate is passed through line 26 to separator 27. Separator 27 is provided with weirs 30 and 31. Condensate in separator 27 separates into three phases separated by interfaces 32 and 33. The lower or heaviest phase is predominantly furfural and contains a small amount of dissolved oil and water. The furfural layer has an upper level at interface 33 and is confined by weir 31. Furfural layer is withdrawn through line 34 and a part is returned as reflux to tower 18 through line 23. The intermediate phase is predominantly water and contains a small amount of dissolved furfural and oil. The water layer has a lower level at interface 33 and an upper layer at interface 32. The water layer overflows weir 31 and is confined by weir 30. Water phase is withdrawn through line 35. If desired, at least a portion of the reflux for tower 18 may comprise water from line 35 passed through line 24 to line 23 thereby supplying a part of the water required to form the azeotrope and reduce the amount of steam introduced through line 21. The upper layer having a lower level at interface 32 is predominantly oil and contains a small amount of dissolved furfural and water. The oil phase overflows weir 30 and is withdrawn through line 36. Oil withdrawn through line 36 is similar to the raffinate discharged through line 4 and may be combined with it before or after separation of dissolved furfural.

Furfural phase withdrawn through line 34 may be passed through lines 37 and 38 to provide a portion of the solvent introduced into tower 11 through line 2. Furfural in line 34 has a water content established by the equilibrium at the temperature and conditions of separator 27. Wet furfural in line 34 is passed through lines 37 and 40 to tower 41. Tower 41 is provided with a reboiler 42. Dry furfural of reduced oil content is withdrawn through line 43 and returned to line 38. Vapor comprising furfural, water and a small amount of oil is withdrawn through lines 44 and 45, condensed in condenser 46, and the resulting condensate is passed through line 47 to separator 50.

Water phase containing dissolved furfural can also be freed of furfural by distillation since the azeotrope of water and furfural is lower boiling than either furfural or water. In this case an azeotrope containing all of the furfural and some of the water is removed overhead from all remaining furfural-free water which is withdrawn as bottoms. Water phase from separator 27 is withdrawn through lines 35 and 51 to water distillation tower 53. Steam is introduced into tower 53 through line 54. Water free of furfural is discharged from the bottom of tower 53 through line 49. Overhead vapor from tower 53, comprising water, furfural, and a small amount of oil, is discharged through line 55 and combined with the similar mixture in line 44 from tower 41 for condensation and separation.

The combined condensates from towers 41 and 53 are passed to separator 50. Separator 50 is similar in design and function to separator 27. Furfural phase having an upper level at interface 60 and confined by weir 57 is withdrawn through line 61 and combined with the furfural phase in line 34 for eventual recycle to extraction tower 11. Water phase between interfaces 60 and 62 overflows weir 57 but is confined by weir 56. Water phase is withdrawn through line 63 and combined with the water from line 35 for furfural separation in water distillation

tower 53. Oil layer separating above interface 62 overflows weir 56 and is withdrawn through line 64. This oil may be combined with oil in line 36 or 4 for furfural separation and recovery, not shown.

The aromatic concentrate-furfural stream withdrawn from tower 18 through line 19 is passed to dry furfural stripping tower 70. Tower 70 is provided with a reboiler 72 to distill remaining furfural out of the aromatic concentrate which is withdrawn from the bottom of tower 70 through line 71. Overhead vapor comprising furfural is discharged through line 73 to condenser 74. Condensed furfural liquid is passed through line 75 to receiver 76. Dry furfural, that is, furfural separated in the absence of a separate liquid water phase, is withdrawn through line 80 and a portion passed through line 81 to tower 70 as a reflux. Remaining dry furfural is passed through line 82 to line 38 for recycle through heater 5 and line 2.

High extraction yields, for example, in excess of about 90 percent of the aromatics contained in the gas-oil feed are obtained in the extraction step of this process. High extraction yields are favored by high solvent ratios and relatively high extraction temperatures. At high extraction yield levels, because of the lower solvent selectivity at conditions favoring high yields, a substantial amount of nonaromatic hydrocarbons is also extracted so that the concentration of aromatics in the extracted hydrocarbon is at least 70 percent and preferably within the range of about 80 to 85 percent. Since most of the aromatics are included in the extract, the raffinate contains very little aromatic hydrocarbon and is therefore particularly valuable in the manufacture of heating oils, diesel fuel oils, catalytic cracking feed stocks and other products where aromatics are undesirable.

In the azeotropic distillation step, the concentration of aromatics in the hydrocarbon portion of the bottoms is increased to about 90 percent or higher by selectively removing nonaromatic hydrocarbons. The azeotropic distillation is effected at a top tower temperature of about 270 to 300° F. and with a bottom tower temperature of about 400 to 550° F. Steam is added at the bottom of the azeotropic distillation tower at a rate of about 0.05 to 3.0 pounds per pound of extract mix to satisfy the composition required to form the azeotrope and to assist in the separation of nonaromatic hydrocarbons from the extract bottoms product. Furfural rich phase, water rich phase or both, separated from the condensed azeotrope distilled overhead, are returned to the azeotropic distillation tower as reflux to provide rectification of the hydrocarbons rising in the tower effecting enrichment in aromatic constituents of the down-flowing liquid.

Example

In accordance with the process of this invention, a gas oil produced by catalytic cracking is treated for recovery of aromatics. The catalytic cracked gas oil charge stock has the following characteristics:

Gravity, °API	30.0
Distillation, ASTM, IBP, °F.	400
Distillation, ASTM, EP, °F.	550
Hydrocarbon analysis, percent by vol.	

Aromatics	55.0
Paraffins	34.0
Naphthenes	11.0

The gas oil charge is contacted at a rate of 2500 barrels per day (b.p.d.) with furfural solvent in a counter-current contactor at a solvent dosage of 200 volume percent. The furfural solvent contains 5.0 volume percent dissolved water and 3.0 volume percent dissolved oil. A temperature gradient of 50° F. is maintained in the contactor with the top temperature (raffinate) of 130° F. and bottom temperature (extract) of 80° F. Raffinate mix is stripped to separate dissolved furfural and produce a raffinate product in a yield of 46.2 volume percent of the charge oil. Extract mix is produced at a rate of 6,445 b.p.d. containing 75.9 volume percent furfural and

24.1 volume percent hydrocarbon, the aromatic content of which is 85 volume percent.

Extract mix at a rate of 6,445 b.p.d. is passed to an azeotropic distillation column together with 143,400 pounds per day of steam. An azeotrope is distilled overhead containing furfural, steam and hydrocarbon and bottoms are withdrawn containing 77.5 volume percent furfural and 22.5 volume percent hydrocarbon having an aromatic content of 93 volume percent. Distillate is condensed separating 170 b.p.d. of oil phase, 460 b.p.d. of water phase and 251 b.p.d. of furfural phase. Bottoms from the azeotropic distillation column are passed to a second distillation column at a rate of 5,975 b.p.d.

Furfural containing substantially no water and 1.0 volume percent oil at a rate of 4,630 b.p.d. is distilled overhead and aromatic concentrate containing 93 volume percent aromatics is withdrawn at a rate of 1,345 b.p.d. as bottoms product.

We claim:

1. A method for the separation of an aromatic rich fraction from a liquid hydrocarbon mixture which comprises:

contacting said mixture with a solvent comprising liquid furfural in an extraction zone separating a raffinate mix comprising a hydrocarbon phase containing dissolved furfural and an extract mix comprising a furfural phase containing dissolved hydrocarbons containing 70 to 85 volume percent aromatic hydrocarbons,

distilling at least a part of said extract mix in a first distillation zone in the presence of added steam in an amount within the range of 0.05 to 3.0 weight percent of said extract mix separating a first distillate comprising water, nonaromatic hydrocarbons and furfural and a first bottoms liquid comprising furfural and hydrocarbons containing at least 90 volume per cent aromatic hydrocarbons, separating said first distillate into a hydrocarbon-rich phase comprising at least a portion of said non-aromatic hydrocarbons, a water-rich phase, and a furfural-rich phase comprising furfural containing dissolved oil and water,

separating at least a portion of said dissolved oil and water from said furfural-rich phase forming a treated furfural-rich phase,

passing said treated furfural-rich phase to said extraction zone as a portion of said solvent,

distilling at least a part of said first bottoms liquid in a second distillation zone separating a second distillate comprising furfural in the absence of a liquid water phase and a second bottoms liquid comprising said hydrocarbons containing at least 90 volume percent aromatic hydrocarbons said second distillate containing less than 0.1 volume percent dissolved water and less than 1.0 volume percent dissolved oil, and

passing said second distillate to said extraction zone as a portion of said solvent.

2. The process of claim 1 wherein said liquid hydrocarbon mixture is a gas oil produced by catalytic cracking.

3. The process of claim 1 wherein the extract mix from said extraction zone contains within the range of 65 to 85 volume percent furfural.

4. The process of claim 1 wherein the furfural in said first distillate is within the range of 3.0 to 30.0 volume percent of the furfural in said extract mix.

5. In a method for the separation of an aromatic fraction containing at least 90 percent by volume of aromatic hydrocarbons from a catalytic cracked gas oil wherein said gas oil is contacted with a liquid solvent comprising furfural at a solvent ratio within the range of about 120 to 300 volumes of solvent to 100 volumes of said gas oil in a solvent extraction zone, and an extract mix comprising furfural and dissolved hydrocarbons containing 70 to 85 volume percent aromatic hydrocar-

bons is withdrawn from said extraction zone, the improvement which comprises:

distilling at least a portion of said extract mix in a first distillation zone in contact with added steam in an amount within the range of 0.05 to 3.0 weight percent of said extract mix separating a first distillate comprising an azeotrope of water, furfural and hydrocarbons from a first bottoms liquid comprising furfural and hydrocarbons containing at least 90 percent aromatic hydrocarbons, by volume, separating said first distillate into a hydrocarbon-rich phase comprising at least a portion of said non-aromatic hydrocarbons, a water-rich phase, and a furfural-rich phase comprising furfural containing dissolved oil and water, separating at least a portion of said dissolved oil and water from said furfural-rich phase forming a treated furfural-rich phase, passing said treated furfural-rich phase to said extraction zone as a portion of said solvent, distilling said first bottoms liquid in a second distillation zone separating a second distillate comprising furfural in the absence of a liquid water phase and containing less than 0.1 volume percent dissolved water and 1.0 volume percent dissolved oil and a second bottoms liquid comprising said aromatic

5

10

15

20

fraction containing at least 90 percent by volume of aromatic hydrocarbons, and passing said second distillate to said extraction zone as a portion of said solvent.

6. The method of claim 5 wherein said solvent extraction zone is maintained with a top temperature of about 130° F. and a bottom temperature of about 80° F.

7. The method of claim 5 wherein said catalytic cracked gas oil boils within the range of about 400 to 550° F. by ASTM distillation.

8. The method of claim 5 wherein said first distillation zone is maintained at a top tower temperature within the range of about 270 to 300° F. and at a bottom tower temperature within the range of about 400 to 550° F.
